UNITED STATES PATENT OFFICE

125,772

DESIGN FOR A SPOON OR OTHER ARTICLE OF FLATWARE

Alfred G. Kintz, Wallingford, Conn., assignor to
International Silver Company, Meriden, Conn.,
a corporation of New Jersey

Application January 10, 1941, Serial No. 97,951

Term of patent 14 years

To all whom it may concern:

Be it known that I, Alfred G. Kintz, a citizen
of the United States, residing at Wallingford,
county of New Haven, State of Connecticut, have
invented a new, original, and ornamental Design
for a Spoon or Other Article of Flatware, of
which the following is a specification, reference
being had to the accompanying drawing, forming
a part thereof.

Fig. 1 is a front elevation of a spoon showing
my new design;

Fig. 2 is a back view of the same; and
Fig. 3 is an enlarged sectional view taken on
the line 3—3 of Fig. 1.

The design is intended for use on sets comprising
spoons, forks, knives and similar articles
of tableware.

I claim:

The ornamental design for a spoon or other
article of flatware, substantially as shown and
described.

ALFRED G. KINTZ.
